UNITED STATES PATENT OFFICE.

WILLIAM DAWSON, OF PHILADELPHIA, PENNSYLVANIA.

BOOK-REST.

SPECIFICATION forming part of Letters Patent No. 431,036, dated July 1, 1890.

Application filed June 24, 1889. Serial No. 315,435. (No model.)

To all whom it may concern.

Be it known that I, WILLIAM DAWSON, of Philadelphia, in the State of Pennsylvania, have invented certain new and useful Improvements in Book-Rests, whereof the following is a specification, reference being had to the accompanying drawings, in which—

Figure 1 is a view illustrating the method of using the rest. Fig. 2 is a view in perspective of the rear side of the rest and its stand. Fig. 3 is a vertical sectional view through the ball-and-socket joint by which the rest is connected with the standard. Fig. 4 is a similar sectional view of the telescoping standard and its locking device. Fig. 5 is a view, on a much-enlarged scale, of the devices for holding the leaves of a book in position. Fig. 6 is a view of the same parts in position to release the leaves. Figs. 7, 8, and 9 are detail views of portions of said device. The scale of Figs. 1 and 2 are much smaller than that of the remaining figures.

Referring to the drawings, A represents a flat base-piece, rounded, as shown, so that it may conveniently be placed upon the seat of a chair and sat upon by the person who is using the rest. At one end of said base-piece is a tubular standard B, into which a second tube C telescopes. At the top of the tube B, I provide a pivoted locking cam or eccentric D, (see Fig. 4), by means of which the tube C may be secured at any desired height. At the top of the tube C is a rounded socket I, in which a ball-joint E fits, said ball-joint being provided with a small overhanging screw-cap H, by means of which it is held in place in the socket. At the bottom of the socket is a round hole, in which fits a plug K, having an inclined or wedge-shaped bottom, against which a thumb-screw J bears so that when said thumb-screw is turned in the plug K will be forced up against the bottom of the ball E, and clamp the upper surface of said ball against the overhanging edge of the screw-cap H, so as to hold the ball in any position in which it may be set in the top of the straight or upright telescoping standard. The ball is attached by means of a short curved neck to a plate L, which supports the book-rack or book-holder F, having a bottom ledge-strip G. This ledge-strip G is made hollow, and contains within its interior most

of the working parts of the leaf-holding devices, now about to be described. They are represented in Figs. 5 to 9, both inclusive. At 55 the center of the piece which forms the ledge-strip G is a pivot e, having a square head f, to prevent its turning, and upon said pivot a disk c, provided with a lever-arm d, rotates freely. A coiled spring g, secured to said pivot and to said disk tends normally to throw the same so as to turn the lever-arm d into the position indicated in Figs. 5 and 7, so that it lies flat against the lower surface of the ledge-strip G and out of the way. Connecting-rods b b' are attached to the disk c diametrically opposite to one another, and extend within the hollow of the ledge-strip G to points a short distance from the ends thereof, where they are pivoted eccentrically 70 to disks h, upon which are mounted split tubes i, having a screw-thread in their interior surface to receive the threaded end k of the bent or cranked finger-pieces a. These tubes are pivoted freely in openings through 75 the outer or front edge of the ledge-strip G, so as to oscillate about their longitudinal axes in order that when the disks h are turned the fingers a will revolve through substantially 80 a quadrant. The split tubes, it will be seen, 85 constitute rock-shafts for the finger-pieces.

The points of attachment of the rods b b' to their respective disks are so situated relatively to one another that when the disk c is in its normal position (shown in Fig. 5) the 85 fingers a will be turned up nearly at right angles to the ledge-strip G, and will consequently press upon the leaves of a book held thereon. When, however, the lever d is thrown out into the position indicated in Fig. 90 6, the shifting of the rods b b' will throw down the fingers a, so that they are nearly parallel with the upper surface of the ledge-strip, and thus free the leaves of the book. The page can then be turned, and as soon as 95 this is done the lever d is released, whereupon the spring g throws the disk c and the lever d back to their normal position, and the fingers a fly up to again hold the leaves.

The threaded mounting of the fingers a permits their adjustment for any thickness of book without affecting in any way their capacity for operation.

I am aware that it is not new to provide

book-rests with telescoping standards and with fingers for holding the leaves of a book, and I do not claim the same; but

I claim—

5 1. A book-rest comprising a broad flat base-piece, having a configuration adapting it to be placed upon a chair-seat to be sat upon by the occupant of the chair, a standard mounted upon the base-piece, and a book-rack supported by said standard, substantially as and for the purpose set forth.

10 2. The combination of the flat base-piece having a configuration adapting it to be sat upon, the upright telescoping standard mounted at its lower end at one end of the base-piece and having the socket at its upper end, the ball fitted in the standard-socket, the clamp for securing the ball against movement, and the book-rack carried by the ball, substantially as and for the purpose set forth.

15 3. The combination of the book-rack having the ledge-strip along its lower edge, the rock-shafts pivoted in openings through the outer or front edge of the ledge-strip, the cranked holding-fingers adjustable lengthwise of the rock-shafts, the disks attached to the rock-shafts, the turning spring-actuated disk supported by the ledge-strip between the holding-fingers, the lever turning beneath the ledge-strip and secured to the spring-actuated disk, and the connecting-rods, each pivoted at one end to one of the rock-shaft disks and at its other end to the spring-actuated disk, substantially as and for the purpose set forth.

WM. DAWSON.
